(57) **CLAIM**

The ornamental design for an insulation boot for an electric device box, as shown and described.

DESCRIPTION

FIG. 1 is a perspective view of an insulation boot for an electric device box of my new design;

FIG. 2 is a front elevational view thereof;

FIG. 3 is a side elevational view thereof, the opposite side being a mirror image thereof;

FIG. 4 is a top plan view thereof;

FIG. 5 is a bottom plan view thereof;

FIG. 6 is a rear elevational view thereof;

FIG. 7 is a sectional view taken along line 7—7 of FIG. 2.

FIG. 8 is a perspective view of a first modification of the insulation boot for an electric device box of FIG. 1;

FIG. 9 is a front elevational view of FIG. 8;

FIG. 10 is a side elevational view of FIG. 8, the opposite side being a mirror image thereof;

FIG. 11 is a top plan view of FIG. 8;

FIG. 12 is a bottom plan view of FIG. 8;

FIG. 13 is a sectional view taken along line 13—13 of FIG. 9; and,

FIG. 14 is an exploded view of FIG. 8.

The broken lines in the drawings depict surface perforations which form part of the claimed design.
